UNITED STATES PATENT OFFICE.

ROBERT L. YEAKY, OF CAVE IN ROCK, ILLINOIS.

DESIGN FOR A CASE FOR MUSICAL INSTRUMENTS.

52,927.

Specification for Design.

Patented Jan. 28, 1919.

Application filed October 10, 1916. Serial No. 124,918. Term of patent 14 years.

To all whom it may concern:

Be it known that I, ROBERT L. YEAKY, a citizen of the United States, residing at Cave in Rock, in the county of Hardin and state of Illinois, have invented a new, original, and ornamental Design for a Case for Musical Instruments, of which the following is a specification, reference being had to the accompanying drawing, forming part hereof.

The figure is a perspective view of a case for musical instruments, showing my new design.

I claim:—

The ornamental design for a case for musical instruments, as shown.

ROBERT L. YEAKY.

Witnesses:

H. C. FRAYSER,
C. C. KERR.
